UNITED STATES PATENT OFFICE

2,320,141

PLOW HITCH

Louis Kott, Fredericksburg, Tex., assignor to
 Fredericksburg Implement Co., Fredericksburg,
 Tex., a partnership

Application September 30, 1942, Serial No. 460,250

3 Claims. (Cl. 97—47)

The present invention relates generally to new and useful improvements in plow hitches, and has for its primary object to provide, in a manner as hereinafter set forth, novel means whereby disk plows may be expeditiously connected to and successfully operated from a tractor which is equipped with a linkage system.

Another very important object of the invention is to provide a hitch of the aforementioned character which may be used without the necessity of making material structural alterations or changes in either the tractor or the plow.

Other objects of the invention are to provide a hitch of the character described which will be comparatively simple in construction, strong, durable, highly efficient and reliable in use, compact, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a top plan view, showing a device constructed in accordance with the present invention in use.

Figure 2 is a view in side elevation thereof.

Figure 3 is a perspective view of the device.

Figure 4 is a view principally in vertical longitudinal section through the device.

Referring now to the drawings in detail, it will be seen that reference character 1 designates generally the rear portion of a tractor which is equipped with a linkage system 2. The linkage system 2 includes tension and compression links 3 and 4, respectively. Journaled between the free end portions of the tension links 3 is a draw bar 5.

The embodiment of the present invention which has been illustrated comprises an angle iron 6 which is secured on the draw bar 5. Welded, at an intermediate point, on the front of the angle iron 6 is a vertical rod 7 of suitable metal. At its upper end, the rod 7 terminates in a fork 8 to which the compression link 4 is pivotally connected at 9. Journaled on the lower portion of the rod or shaft 7 is a sleeve 10. Fixed on the sleeve 10 is a plate 11. A tube 12 is fixed horizontally on the plate 11.

An elongated bolt 13 secures one end portion of a pair of angular arms 14 to the ends of the tube 12. A bushing or bearing 20 is provided in the tube 12 for the bolt 13. Mounted trans-

versely on the other end portions of the arms 14 is a tool bar 15 to which the beams 16 of the disk plow 17 are connected. The rear wheel guide rod 18 of the plow 17 is connected to one end portion of the angle iron 6 through the medium of an eye bolt 19 on said angle iron.

It will thus be seen that a construction and arrangement has been provided whereby a plow unit of the character mentioned may be successfully operated in conjunction with a tractor equipped with a linkage system. To attach the device to the tractor it is only necessary to secure the angle iron 6 on the draw bar 5 and connect the compression link 4 to the upper end portion of the rod or shaft 7. The sleeve 10 journaled on the lower portion of the vertical rod or shaft 7 permits swinging movement of the implement in a horizontal plane while the pivotal connection of the arms 14 to the tube 12 allows for vertical swinging movement.

It is believed that the many advantages of a hitch constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

30. What is claimed is:

1. The combination with a tractor including a hydraulic implement control comprising tension and compression links and a draw bar extending between the tension links, of a vertical shaft fixed, at an intermediate point, on the draw bar and having its upper end pivotally connected to the compression link, a sleeve journaled on the lower portion of the shaft, arms mounted for swinging movement on said sleeve, and a tool bar mounted on said arms.

2. The combination with a tractor comprising a hydraulic implement control including tension and compression links and a draw bar mounted between said tension links, of an angle iron 45 mounted on the draw bar, a vertical shaft fixed, at an intermediate point, on said angle iron and having its upper end pivotally connected to the compression link, a sleeve journaled on the lower portion of the shaft, a tube fixed horizontally on said sleeve, arms mounted for swinging movement on the tube, and a tool bar mounted on said arms.

3. The combination with a tractor comprising a hydraulic implement control including tension links, a compression link and a draw bar ex-

tending between said tension links, of an angle iron mounted on the draw bar, a vertical shaft, fixed, at an intermediate point, on said angle iron and having its upper end portion pivotally connected to the compression link, a sleeve journaled on the lower portion of the shaft, a metallic plate fixed vertically on said sleeve, a horizontal

5 tube fixed on said plate, a pair of angular arms, an elongated bolt securing said arms, at one end, to the end portions of the tube, and a tool bar mounted transversely on the free end portions of the arms.

LOUIS KOTT.
